W. SANDS

COVER FASTENER

Filed Nov. 8, 1923.

Richard Kilgore

UNITED STATES PATENT OFFICE.

WALTER SANDS, OF MINNEAPOLIS, MINNESOTA.

COVER FASTENER.

Application filed November 8, 1923. Serial No. 673,558.

To all whom it may concern:

Be it known that I, WALTER SANDS, a citizen of the United States, residing at Minneapolis, in the county of Hennepin and State of Minnesota, have invented certain new and useful Improvements in Cover Fasteners; and I do hereby declare the following to be a full, clear, and exact description of the invention, such as will enable others skilled in the art to which it appertains to make and use the same.

My invention relates to shipping boxes, the term "box" being used in a broad enough sense to include crates, and provides an extremely simple and highly efficient cover, the term "cover" being used in a sense broad enough to include the bottom or any other one of the side-forming members of the box. The cover includes fastening means or locks, which, by the spring action of the cover, are detachably held in interlocking engagement with the sides of the box. This improved cover, while capable of application to boxes generally, will, nevertheless, be especially desirable for use in connection with what is known as collapsible or knock-down shipping boxes or crates such as used for shipping poultry and various bulky articles and where the cost of the shipping box or crate is a considerable item of cost as compared with the contents of the box. Boxes or crates of the above character are easily made collapsible because of the greatly reduced cost in the return shipment of the empty box. My invention also includes an extremely simple yet highly efficient hinge for connecting the four collapsible sides of collapsible shipping boxes or crates.

Generally stated, the invention consists of the novel devices, construction and combinations of parts hereinafter described and defined in the claims.

In the accompanying drawings, which illustrate the invention, like characters indicate like parts throughout the several views.

Referring to the drawings:

Fig. 1 is a perspective showing my invention applied to a collapsible box;

Fig. 2 is a vertical section taken on the line 2-2 of Fig. 1;

Fig. 3 is a detail in transverse section on the line 3-3 of Fig. 2;

Fig. 4 is a fragmentary horizontal section on the line 4-4 of Fig. 1;

Fig. 5 is a fragmentary elevation of parts 55 of the box found in the vicinity of the line marked 5-5 on Fig. 4;

Fig. 6 is a fragmentary view showing a slight modification of the hinge illustrated in Fig. 4, the same being taken on the same section line as Fig. 4; and

Fig. 7 is a view corresponding to Fig. 4, but illustrating a still further modification of the hinge structure.

The box, as shown, has four flat sides 8 of solid construction, but these sides, of course, will be made up of slats when a box of the crate type is desired. At the corners of the box, the four sides 8 are connected by hinges, each hinge comprising a pair of staples or U-shaped wires 9 that are driven obliquely through the end portions of the side members, as best shown in Fig. 4. One staple of each hinge lies in a horizontal plane and the other is set edgewise in a vertical plane and the ends of the staples are clinched or bent against the exterior of the sides. This provides an efficient hinge of very trifling cost. By driving the staples obliquely through the box sides, their interlocked portions are brought at the proper places to permit the four side members to fold together flatwise when the box is collapsed.

The hinge shown in Fig. 6 is like that shown in Fig. 4, except that the projecting loops of the staples 9^a are contracted so as to form nearly circular eyes 9^b. The hinge shown in Fig. 7 is formed of two eye-bolts 10 having interlocked eyes, the said eye-bolts 9^c being driven obliquely through the sides of the box at the corners thereof and having their ends clinched at the exterior of the box side members.

In this type of folding box, the cover or top and the bottom of the box may be assumed to be of substantially the same construction and, hence, only the top or cover member will now be specifically described. This cover, as well as the sides of the box, 100 may take various forms but is preferably of skeletonized or crate-like type and, in fact, there is important minor novelty in the way in which this cover is made as well as in the way in which the cover fasteners 105 are applied thereto. As shown, said cover is made up of parallel longitudinally spaced rails 11 and transverse slats 12 and, as an

important feature, the side rails 11 are each made up of two slats placed one on top of the other and nailed or otherwise rigidly secured together and the ends of the cross slats 12 are nailed or otherwise rigidly secured to said side rails.

In this preferred arrangement, the front and rear side plates of the box project slightly above the inside plates, and the side rails 10 12 of the cover are so spaced and of such length that they will fit flush between the upper edges of said front and rear plates and their ends will rest upon the end plates, as clearly shown in Figs. 1 and 2.

15 The preferred form of the improved fastener is best shown in detail in Fig. 3, but is also shown in other views. Each such fastener is in the form of a metallic slide 13 with upturned inner end 14 and upturned outer 20 end 15. These fasteners are arranged to slide through the rails 11, which are provided with guide passages formed by cutting grooves 16 in the upper faces of the lower cleats of said side rails before the two 25 cleats are secured together and, of course, the fasteners should be inserted in said slots before the two cleats are nailed or otherwise secured together. By reference to Fig. 2, it will also be noted that certain of the cross 30 slats 12 are located directly under the grooves 16 and that clinched nails 17 are driven through the rails and through the ends of said cross slats on opposite sides of the said slots. This not only provides cheap 35 construction but reinforces the side rails at points where they would be otherwise slightly weakened by the slots.

The front and back plates of the box, for 40 cooperation with the outer ends of the sliding fasteners 14, are formed with angular perforations 18 through which the outer end flanges 15 may be freely slid when and only when the cover is sprung downward, so that said flanges will align with said perforation. Of course, the slides 13 must be long enough to project completely through the perforations 18 and into engagement with the exterior of the front and back plates, as shown in Figs. 1 and 3.

45 50 When the cover is first placed on the top of the box, as shown in Fig. 1, its side rails 11 will be approximately flush with the upper edges of the front and back plates and the fasteners 13 and their outer flanges 15 will then stand above the perforations 18, but by springing the intermediate portion of the cover downward, the fasteners may be aligned with and then forced outward through the perforations 18 and then, when 55 60 the pressure is removed from the cover, it will spring up into the position shown in Fig. 3 and return as nearly to normal position as permitted by the slots 18. When the fasteners are engaged with the box, as shown 65 in Fig. 3, the cover will not only be firmly

held in position but the front and rear plates of the box will be tied together and prevented from outward bulging movements and, of course, there is no chance of the fasteners becoming accidentally uncoupled from the sides of the box because their release from the box requires first that the cover be properly sprung downward or depressed and that, while thus properly depressed, all of the fasteners be slid inward from operative 70 positions, and no such actions could possibly take place except by intended manipulations.

The fastener described may take different forms but, advisably, they are stamped or 80 bent from flat rolled steel or thin iron bars or sheets.

The feature of providing a box cover or removable side-forming member with fasteners movable into and out of interlocking 85 engagement with the box proper and arranged to be normally held interlocked therewith by the spring tension in the cover member, is considered broadly new, irrespective of the manner in which they are 90 applied and of the manner in which the cover is arranged to be sprung in order to effect engagement of the fasteners with the box or disengagement of the fasteners from the box.

95 What I claim is:

1. The combination with a box, of a cover therefor adapted to be sprung in respect to its normal position of rest on the box and provided with fasteners adapted for interlocking engagement with the box and arranged to be held interlocked with the box by the spring tension of the cover.

2. The combination with a box, of a cover therefor adapted to be sprung in respect to its normal position of rest on the box and provided with movable fasteners constructed for interlocking engagement with the box and arranged to be held in interlocking engagement therewith by the spring tension of said cover.

3. The combination with a box, of a cover therefor adapted to be sprung in respect to its normal position of rest on the box and provided with sliding fasteners having bent 115 ends insertable through openings in the box and adapted for interlocking engagement with the box.

4. The combination with a box, of a cover therefor adapted to be sprung in respect to 120 its normal position of rest on the box and provided with sliding fasteners having bent ends insertable through openings in the box and adapted for interlocking engagement with the box and arranged to be held interlocked with the box by the spring tension of said cover.

5. The combination with a box, of a cover therefor adapted to be sprung in respect to its normal position of rest on the box and 130

- provided with fasteners in the form of flat metal slides having outturned ends permitting said fasteners limited sliding movements, said box having openings through which the outer flanged ends of said slides may be moved when the cover is sprung, and the said fasteners being held in interlocking engagement with the box by the spring tension of said cover.
6. A box cover made up of longitudinal bars and cross slats, said bars each being made up of two slats, one of which has notches facing the companion slat, and fasteners in the form of flat metal pieces arranged to slide through the passages formed by said notches and provided with outturned ends limiting the sliding movements thereof, the projecting ends of said fasteners being adapted for interlocking engagement with the box.
7. The structure defined in claim 6 in which nails are driven through the slats of
- said bars on opposite sides of the fasteners and are driven into aligned cross slats.
8. The combination with a box having 25 sides that project slightly above its ends, said sides having fastener passages in the vicinity of its upper edge, of a cover comprising laterally spaced bars and cross slats, said bars being of a length to rest on the 30 upper edges of the ends of the box, and sliding fasteners working through said bars and having bent ends insertable through the fastener passages of the sides of the box and adapted for interlocking engagement 35 therewith.
9. The structure defined in claim 8 in which said fasteners may be engaged through the fastener passages of said box only when the intermediate portions of the 40 bars of said cover are sprung inward.

In testimony whereof I affix my signature.

WALTER SANDS.
